[57] CLAIM

The ornamental design for a medical trolley for carrying resuscitation equipment, as shown and described.

DESCRIPTION

FIG. 1 is a front perspective view of a medical trolley for carrying resuscitation equipment, showing our new design;

FIG. 2 is a rear elevational view thereof;

FIG. 3 is a side elevational view thereof; and

FIG. 4 is a top plan view thereof.

The bottom of the article is substantially plain and unornamented.

FIG. 1.

FIG. 2.

FIG. 3.

FIG. 4.
